UNITED STATES PATENT OFFICE.

REINHOLD KRUMMING, OF MILWAUKEE, WISCONSIN.

TEMPORARY BINDER OR LOOSE-SHEET HOLDER.

1,091,146.

Specification of Letters Patent. Patented Mar. 24, 1914.

Application filed January 6, 1913. Serial No. 740,450.

To all whom it may concern:

Be it known that I, REINHOLD KRUMMING, a citizen of the United States, residing at Milwaukee, Wisconsin, have invented certain new and useful Improvements in Temporary Binders or Loose-Sheet Holders, of which the following is a specification.

This invention relates to improvements in temporary binders or loose sheet holders. 10 The main objects of this invention are: First, to provide in a temporary binder, an improved adjusting means. Second, to provide an improved temporary binder of the post type which is simple and economical in structure and one which is at the same time 15 very easily manipulated and satisfactory in use. Third, to provide in a temporary binder, an improved post.

Further objects, and objects relating to 20 structural details will definitely appear from the detail description to follow.

I accomplish the objects of my invention by the devices and means described in the following specification.

25 The invention is clearly defined and pointed out in the claims.

A structure which is a preferred embodiment of my invention is clearly illustrated in the accompanying drawing forming a 30 part of this specification, in which:

Figure I is a detail inside plan of a structure embodying the features of my invention, the covers being open or extended. Fig. II is an enlarged detail section taken 35 on a line corresponding to line 2—2 of Fig. I. Fig. III is a perspective view of the cover members 3 and 4 with the binding omitted. Fig. IV is a detail section on a line corresponding to line 4—4 of Fig. II. Fig. V is a detail section on a line corresponding to line 5—5 of Fig. II. Fig. VI is a detail section on a line corresponding to line 6—6 of Fig. IV. Fig. VII 40 is an enlarged detail section on a line corresponding to line 7—7 of Fig. I. Fig. VIII is a detail section of the cover members, on a line corresponding to line 8—8 of Fig. I. Fig. IX is a detail perspective of one of the post members 8 before the same 45 is attached to the cover member. Fig. X is a perspective view of one of the attaching members 15.

In the drawing similar reference characters refer to similar parts throughout the 50 several views, and the sectional views are

taken looking in the direction of the little arrows at the ends of the section lines.

Referring to the drawing, the structure illustrated is provided with covers 1 and 2 which are provided with binding members 3 and 4 respectively. The binding members are connected to the covers by suitable flexible hinges 5. The binding or cover members 3 and 4 are provided with inwardly projecting telescoping back members or portions 6 and 7 respectively, which form the back of the binder. Each cover member and its respective back member are preferably formed integral, the same being pieces of sheet metal bent into angular form, as 70 shown. The binding posts are made up of outer members 8 secured to the cover members 3 and inner members 9 secured to the cover members 4. The inner post members are adapted to telescope into the outer members, as clearly illustrated in Fig. II. The post members 8 are preferably provided with web-like shanks 10 on their rear edges, the shanks being provided with securing tongues 11, while the post has downwardly 75 projecting securing tongues 12, on its lower end. The post member 8 and its shank 10 and the tongues on the shank and post are preferably formed integral of a piece of sheet metal folded upon itself as clearly 80 shown in the drawing.

The cover member 6 is provided with slots 13 in its back portion through which the tongues are arranged and clamped upon the outer side of the back portion. The 90 tongues 12 are arranged through openings 14 in the cover member 3 and clamped over the attaching members 15. The tongues 12 are formed by cutting away opposite sides of the post, as shown in Fig. IX. The attaching member 15 is spool-shaped, the tongues being folded inwardly over the narrow portion thereof as illustrated. This forms a very rigid and secure attaching means for the posts without the use of 95 solder or threaded parts. The attaching means is of importance as it will be readily understood that it is a desirable feature to attach the posts on which strain is put in use to the sheet metal cover members securely and at the same time in a manner that leaves no objectionable projecting parts.

The inner posts are adjustably secured within the outer posts by providing the clamping or engaging members 16 which 100

105

110

are mounted on pivots 17 carried by the inner posts, the inner posts being slotted at 18 to permit the engaging or clamping member being swung into engagement with the walls of the outer post member, as shown in Fig. IV. The engaging or clamping member 16 is actuated by the actuating member 19 provided with an actuating screw 20, the member 19 being longitudinally slotted at 21 to receive the engaging member, the ends of the slots acting on the edges of the engaging member to swing it into and out of its engaging position, the member being actuated to impinge on or clutch the walls of the outer post member when the actuating member 19 is drawn up by its screw and being released when that member is forced down, as by the spring 22,—see Figs. II and IV. The head of the screw 20 is slotted at 23 to receive a screw driver, key, or the like. The spring 22 bears against the collar 24 secured to the cover member 4. When the screw is turned to release the actuating member the actuating member is pushed inwardly by the spring 6, throwing the member 16 out of engagement. I sometimes provide the screws with suitable finger pieces instead of slotting them, as illustrated.

The pivot 17 in the structure illustrated is extended at one end to engage the groove 25 formed by the shank 10. This prevents the turning of the inner post member or the attaching member which is slotted at 26,—see Fig. II—to receive the pivot.

The center post is not provided with adjusting means, but is provided with means for extending the binder when the adjusting means is released, a spring 27 being arranged in the outer post member 28 to engage the inner post member 29. See Fig. VII.

To assist in supporting the parts in alignment, the back member 7 is provided with a flange 30 which embraces the edges of the back member 6, as clearly shown. The end of the tubular actuating member 19 is longitudinally crimped as shown in Fig. VI to reduce its bore, the portion so reduced being internally threaded to receive the adjusting screw 20.

As previously stated, my improved binder is very simple and economical in structure, and is at the same time easily and quickly adjusted and very durable.

I have illustrated and described a preferred form of my improvements. Various modifications will, however, readily suggest themselves to those skilled in the art to which this invention relates; I desire, however, to claim my improvements specifically in the form illustrated as well as broadly within the scope of the appended claims.

Having thus described my invention, what I claim is new and desire to secure by Letters Patent is:

1. In a binder, the combination of an

outer post member having a longitudinal groove therein, an inner post member having a longitudinal slot therein, arranged to telescope within said outer post member, an engaging member pivoted within said inner post member to engage the outer post member through said slot, the end of the engaging member pivot being extended to engage said groove in said outer post member, an actuating member disposed within said inner post member and longitudinally slotted to receive said engaging member, the ends of the slot engaging said engaging member to rock it on its pivot, an adjusting screw whereby said actuating member is moved longitudinally, a spring arranged within said inner post member for returning said actuating member to its releasing position, said spring being arranged upon said screw, and a collar supporting the outer end of said spring.

2. In a binder, the combination of an outer post member; an inner post member having a longitudinal slot therein, arranged to telescope within said outer post member, an engaging member pivoted within said inner post member to engage the outer post member through said slot, an actuating member disposed within said inner post member and longitudinally slotted to receive said engaging member, the ends of the slot engaging said engaging member to rock it on its pivot, an adjusting screw whereby said actuating member is moved longitudinally, a spring within said inner post member for returning said actuating member to its releasing position, said spring being arranged upon said screw, and a collar supporting the outer end of said spring.

3. In a binder, the combination of an outer post member having a longitudinal groove therein, an inner post member having a longitudinal slot therein, arranged to telescope within said outer post member, an engaging member pivoted within said inner post member to engage the outer post member through said slot, the end of the engaging member pivot being extended to engage said groove in said outer post member, an actuating member disposed within said inner post member and longitudinally slotted to receive said engaging member, the ends of the slot engaging said engaging member to rock it on its pivot, an adjusting screw whereby said actuating member is moved longitudinally, a spring arranged within said inner post member for returning said actuating member to its releasing position.

4. In a binder, the combination of an outer post member, an inner post member having a longitudinal slot therein, arranged to telescope within said outer post member, an engaging member pivoted within said inner post member to engage the outer post

member through said slot, an actuating member disposed within said inner post member and longitudinally slotted to receive said engaging member, the ends of the slot engaging said engaging member to rock it on its pivot, an adjusting screw whereby said actuating member is moved longitudinally, and a spring arranged within said inner post member for returning said actuating member to its releasing position.

5. In a binder, the combination of an outer post member having a longitudinal groove therein, an inner post member having a longitudinal slot therein, arranged to telescope within said outer post member, an engaging member pivoted within said inner post member to engage the outer post member through said slot, the end of the engaging member pivot being extended to 10 engage said groove and said outer post member, an actuating member disposed within said inner post member and longitudinally slotted to receive said engaging member, the ends of the slot engaging said 15 engaging member to rock it on its pivot, an adjusting screw whereby said actuating member is moved longitudinally.

6. In a binder, the combination of an outer post member, an inner post member 20 having a longitudinal slot therein, arranged to telescope within said outer post member, an engaging member pivoted within said inner post member to engage the outer post member through said slot, an actuating member disposed within said inner post member and longitudinally slotted to receive 25 said engaging member, the ends of the slot engaging said engaging member to rock it on its pivot, an adjusting screw whereby said actuating member is moved longitudinally.

7. In a binder, the combination of an outer post member, an inner post member arranged to telescope within said outer post member, an engaging member pivoted with- 30 in said inner post member to engage the outer post member, an actuating member disposed within said inner post member, an adjusting screw for said actuating member, and a spring for returning said actuating 35 member to its releasing position.

8. In a binder, the combination of an outer post member, an inner post member arranged to telescope within said outer post member, a pivoted engaging member carried by said inner post member, an actuating member provided with an adjusting screw, whereby said engaging member may be rocked on its pivot and clamped against the outer post member, and a spring for re- 40 turning said actuating member to its releasing position when released by said screw.

9. In a temporary binder, the combination of the telescoping posts, means for adjustably securing said posts together comprising 45 an engaging member, a tubular actuating

member therefor, an adjusting screw for said actuating member, said tubular actuating member being crimped longitudinally to reduce its bore, the portion so reduced being internally threaded to receive said screw. 70

10. In a binder, the combination of a binding post having a flat shank on its rear side, said post being provided with attaching tongues on its lower end, said shank being provided with attaching tongues on its 75 rear edge, said post, shank, and tongues being formed integrally of a piece of sheet metal folded upon itself, an angled cover member having slots in one arm through which the tongues of said shank are engaged, the other arm of the cover member being provided with an opening for the tongues of said post, and an attaching member on the outer side of such arm over which said tongues are clamped. 80

11. In a binder, the combination of a binding post having a flat shank on its rear side, said post being provided with attaching tongues on its lower end, said post, shank, and tongues being formed integrally 85 of a piece of sheet metal folded upon itself, an angled cover member, said shank attached to one arm of said cover member, the other arm of the cover member being provided with an opening for the tongues of 90 said post, and an attaching member on the outer side of such arm over which said tongues are folded. 95

12. In a binder, the combination of a binding post having a flat shank on its rear side, said post being provided with attaching tongues on its lower end, said shank being provided with attaching tongues on its 100 rear edge, said post, shank, and tongues being formed integrally of a piece of sheet metal folded upon itself, and an angled cover member having slots in one arm through which the tongues of said shank are engaged, the post being attached to the other arm of said cover member, the attaching 105 means comprising the tongues on said post. 110

13. In a binder, the combination of an outer post member, an inner post member having a longitudinal slot therein, arranged to telescope within said outer post member, means for adjustably securing said post members together comprising an engaging member mounted on a pivot within said inner post member to engage the outer member through said slot, and an actuating 115 member arranged within said inner post member for movement longitudinally thereof and engaging opposite sides of said engaging member, whereby said engaging member is positively rocked on its said pivot 120 into engaging and disengaging position. 125

14. In a binder, the combination of an outer post member, an inner post member arranged to telescope within the outer post member, an engaging member mounted on a 130

pivot carried by said inner post member, and an actuating member arranged within said inner post member to engage opposite sides of said engaging member, whereby it is positively rocked on its pivot and clamped against the outer member when the actuating member is actuated to engage the same and is positively rocked on its pivot to release the same when the actuating member is

actuated in the opposite direction, all coast- 10 ing for the purpose specified.

In witness whereof, I have hereunto set my hand and seal in the presence of two witnesses.
